(57) **CLAIM**

The ornamental design for a bottle, as shown and described.

DESCRIPTION

FIG. 1 is a perspective view of a bottle showing our new design;

FIG. 2 is a top view;

FIG. 3 is a side elevational view from the direction indicated in FIG. 2;

FIG. 4 is a side elevational view from the direction shown in FIG. 2;

FIG. 5 is a side elevational view from the direction shown in FIG. 2;

FIG. 6 is a side elevational view from the direction shown in FIG. 2;

FIG. 7 is a bottom view thereof; and,

FIG. 8 is a sectional view taken along a line 8—8 in FIG. 6. The dotted lines in the drawing are for environmental purposes and form no part of the claimed design.
